(57) CLAIM

The ornamental design for a golf decanter set, as shown and described.

DESCRIPTION

FIG. 1 is a top, front right perspective view of a golf decanter set;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof; and,

FIG. 7 is a bottom plan view thereof.

In the drawings, the broken lines show portions of a golf decanter set that form no part of the claimed design.

1 Claim, 7 Drawing Sheets
